UNITED STATES PATENT OFFICE.

ORIN E. MARVEL, OF DAYTON, OHIO.

ELECTRICAL TRANSMITTER FOR AURAL RECEPTION.

Application filed June 29, 1920. Serial No. 392,825.

To all whom it may concern:

Be it known that I, ORIN E. MARVEL, a citizen of the United States, residing at Dayton, in the county of Montgomery and 5 State of Ohio, have invented certain new and useful Improvements in Electrical Transmitters for Aural Reception, of which the following is a specification.

This invention relates to electrical transmitters for aural reception.

An object of this invention is to provide a transmitter for electrical reception which is uninfluenced by the passage of strong wind and inert toward noises extraneous of the 15 sounds or speech transmitted.

In the preferred form of my invention the transmitter is adapted to be positioned at the throat of the operator and is constructed and arranged to permit proper body movement of the operator incident to driving or 20 operating airplanes, automobiles or the like, and to be sealed automatically against the flow of high wind current and against the reception of influence of extraneous noises.

25 In the preferred form of my invention the transmitter comprises two transmitter buttons, each button including a movable electrode adapted to vibrate corresponding to the vibrations of the neck of the operator on opposite sides of the esophagus, the remaining electrodes being relatively fixed, and mounting means for such buttons and the electrical elements connecting the same with a telephone wiring arrangement. Such vibration responsive relation may be readily effected by the provision of a diaphragm of suitable resilient material and suitable vibration transmitting means connecting such diaphragm with its movable electrode.

40 Further features and objects of the invention will be more fully understood from the following description and the accompanying drawings, in which

Fig. 1 is a horizontal sectional view of one 45 form of my invention;

Fig. 2 is a side elevation of Fig. 1 as viewed from line 2—2 of Fig. 1 showing the band 3 removed;

Fig. 3 is a sectional elevation on the line 50 3—3 of Fig. 1 showing the band 1 removed.

Figure 4 is a section of one of the transmitter buttons showing the same in detail.

Referring to the drawings, the invention is shown in an embodiment of the type for use about the throat of the operator, and 55 for such purpose the band 1 of leather is

provided having, as shown in Fig. 1, the general contour of the neck of a person, such band 1 being provided with suitable fastening means 2 for clasping the same at the back of the neck. The outer band 3 connects with the inner band 1 from the location 4 forwardly and to the location 5, resulting in a general crescent-like formation, within which are the oppositely disposed blocks of 60 sponge rubber 6, 7, and the forwardly disposed block of sponge rubber 8.

Suspended by such blocks of sponge rubber is the bent strip 9, of general circular form but more or less arched at 10, 11, for 70 the support of the two transmitter buttons.

As shown, each transmitter button comprises the fixed electrode 12, removably mounted on the contact lug 13 and movable electrode 14, which is held by a mica disk 75 in the electrode case 15' with carbon granules 12'' therebetween, in the customary manner. To such movable electrode 14 is connected an armature of soft and resilient material 14' such as sponge rubber, one part 80 of which is adapted to be placed in contact with the throat of the operator, and the second part, 14'', which is held suspended at its circular edge within the annulus portion 16 of the strip 15, which may be of 85 aluminum or other suitable rigid and light material. The part 14'' serves as a diaphragm or a transmitting part to transmit the vibrations of the throat of the user to the movable electrode. A resilient strip of 90 metal 17 is held between the strip 15 and the bent strip 9, and this strip 17 is suitably bent as shown in Figure 1 and bears against the part 14'' of the armature.

The electrical connection between the two 95 transmitter buttons is similar to the connection of ordinary telephone transmitters, and for this reason the particular use of the transmitter and its electrical connections with a radio receiving and transmitting set is 100 not shown.

Upon articulation by the operator, the outer wall of the operator's neck adjacent to the esophagus is vibrated in correspondence to the sounds emitted by the operator 105 through his mouth, thereby vibrating the armatures of sponge rubber, and therewith the movable electrodes, thus modifying the electrical current passing through the telephone circuit in which the transmitter buttons are connected. The crescent or U-shape of the supporting bar 9 serves to 110

maintain the fixed electrodes which are mounted on the supporting bar, in a relatively stationary position as regards the neck of the user, and the movable electrode 5 with the sponge rubber armature connected thereto will have a small moment of inertia, so as to freely vibrate in correspondence with the vibrations of the user's throat.

I have discovered that the particular construction of my invention is readily and conveniently carried by the operator in the performance of the duties of piloting or operating an aeroplane, or of driving an automobile, and that the effect of high wind currents on the transmitter is entirely precluded, notwithstanding that the operator opens his mouth during the stage of transmitting. I have also discovered that my invention effectively renders inert the noises attending the explosions of the airplane engine and the revolutions of the propeller, as well as other noises extraneous of the speech or sound desired to be transmitted.

Whereas I have described my invention by reference to specific forms thereof, it will be understood that many changes and modifications may be made without departing from the spirit of the invention, as defined by the appended claims.

30 **What I claim is:**

1. A telephone transmitter comprising a set of relatively movable electrodes, means for supporting one of said electrodes in a position fixed in relation to a vocal organ 35 of the user, means for supporting a second electrode of said set movable in relation to the fixed electrode, a sponge rubber armature connected to said mentioned one electrode and adapted to be placed in contact 40 with a vocal organ of the user, and electrical connections for the said electrodes.

2. A telephone transmitter comprising a set of relatively movable electrodes, means for supporting one of said electrodes in a position substantially fixed in relation to a vocal organ of the user, means for supporting a second electrode of said set movable in relation to said fixed electrode, and sponge rubber cushioning means connected 50 to said one fixed electrode and adapted to be placed in contact with a vocal organ of the user, said one fixed electrode having a small moment of inertia so as to freely vibrate in correspondence with the movements 55 of the cushioning means.

3. A telephone transmitter comprising a plurality of sets of relatively movable elec-

trodes, a substantially U-shaped rigid supporting member upon which one electrode of each set, in fixed position, is mounted, one 60 on each leg of the U, means for movably supporting a second electrode of each set adjacent the fixed electrode of each set, means connected to said movable electrodes and adapted to be placed in contact with 65 the throat of the user, and electrical connections to the several electrodes.

4. A telephone transmitter comprising two transmitter buttons, each button having a fixed and a movable electrode, means for supporting said buttons adjacent the throat of the user, on opposite sides thereof, comprising inner and outer bands of flexible material, spaced blocks of yielding material disposed between said bands, and a rigid 75 member upon which the fixed electrode of each button is rigidly mounted, supported by said blocks, and yielding means connected to each movable electrode and adapted to be placed in contact with the throat of the 80 user.

5. A telephone transmitter comprising a plurality of sets of relatively movable electrodes, yieldingly arranged means for supporting said sets and constructed to be positioned adjacent the throat of the operator, said supporting means comprising an inner band of flexible material, an outer band of flexible material, spacially disposed blocks of yielding material secured between said 90 two bands, and a strip of rigid material supported by said blocks, said sets of electrodes being disposed between said blocks and mounted on said strip, and a diaphragm for each set of electrodes of resilient material 95 carried by said supporting means and arranged to vibrate in correspondence to the vibration of the walls of the throat of the operator and to transmit such vibrations to its respective electrode.

6. A telephone transmitter comprising a transmitter button having a fixed and a movable electrode, means for supporting said fixed electrode in a stationary position adjacent the throat of the user, comprising 100 a U-shaped rigid strap adapted to extend partially around the throat of the user, and blocks of yielding material upon which said strap is mounted, so that the movable electrode will be placed adjacent the throat of 110 the user.

In testimony whereof I have affixed my signature.

ORIN E. MARVEL.
